TOY SILO FILLER

Frank E. Thomas, Chicago, Ill.

Application September 29, 1942, Serial No. 460,097

4 Claims. (Cl. 46—40)

This invention relates to toy silo fillers where-in a mechanism is to provide a continuous showering of confetti, sand, or similar material which may represent ensilage usually deposited in actual silo structures.

One object of my invention is to provide motive power means in connection with a silo structure connected with a series of pick-up and dumping buckets secured to a continuous conveyer system so as to furnish a toy which will be both educational and amusing to study and to operate.

An important object of my invention is to provide a flexible connecting means which will maintain the contents within the bucket means mounted on the conveyer system while in inverted position and until the bucket assumes a substantially erect position so as to confine the contents and maintain the same within the buckets during the travel in the inverted position.

Other objects, features and advantages residing in my invention will become apparent from reference to the accompanying drawings and the ensuing description, wherein like symbols are used to designate like parts, and in which;

Fig. 1 represents a front view of my invention with certain portions broken away in order to more clearly elucidate the mechanical structure thereof.

Fig. 2 is a top plan view looking down on the view shown in Figure 1.

Fig. 3 is an enlarged top plan view of the bucket means utilized as a part of my invention and showing the mounting thereof.

Fig. 4 is a front view of the view shown in Figure 3.

Fig. 5 is a fragmentary side elevation of the view in Figure 4 more clearly elucidating the particular structure which aids in retaining the contents of the said bucket means while in inverted relationship.

Fig. 6 is an enlarged fragmentary view showing the method of securing the bucket means to the conveyer or belt structure, taken on line 6—6 of Figure 4.

Fig. 7 is a schematic diagram showing the manner in which the lighting and motive power may be connected in a circuit for operating the invention.

Fig. 8 is a transverse cross-sectional view on the line 8—8 of Figure 1.

Fig. 9 is a longitudinal cross-sectional view on the line 9—9 of Figure 2.

Fig. 10 is a longitudinal cross-sectional view on the line 10—10 of Figure 2.

Fig. 11 is a longitudinal cross-sectional view on the line 11—11 of Figure 12.

Fig. 12 is a longitudinal cross-sectional view on the line 12—12 of Figure 2.

Fig. 13 is a longitudinal cross-sectional view on the line 13—13 of Figure 12, also indicated as a transverse cross-sectional view on the line 13—13 of Figure 2.

Fig. 14 is a transverse cross-sectional view on the line 14—14 of Figure 11.

Referring to the various figures, 15 generally designates my invention as a whole, and it is comprised of a base 20 having a hub projection 19 to which my silo generally designated 16 may be removably secured. The silo structure should be preferably made of a transparent plastic material which may be colorless or any light shade of color not interfering with its transparency. The silo body 16 is provided with a hemispherically shaped dome 17 and is secured removably at the beaded portion 18. To this silo is connected a shaft 29 upon which are mounted the V grooved pulleys 30, the pulleys on the shafts 35 and 33 respectively cooperate with this idler pulley in confining the movement of the conveyer 32 in a well defined orbit. Upon these shafts are mounted respectively the pulleys 36 and 34 which are also V grooved in order to accommodate the V belting 32 thus insuring fine traction and minimizing slippage. Upon the belting a number of buckets 31 are provided and as indicated in detail in Figure 3, Figure 4, Figure 5, and Figure 6, the method of attachment and the structure of the bucket is more clearly elucidated.

30 The bucket means is comprised of two end panels 37 being more or less semi-circular in shape and being interconnected by a curved body surface thus providing a semi-cylindrically shaped opening 42. The ends 37 as indicated in Figure 5, project beyond the surface of the opening 42 and are slightly flared outwardly as indicated at 38. Within the buckets, at points shown, the rollers 39 are mounted so that when the conveyer belt moves these buckets when in an inverted position as shown in Figure 1, whence they are caused to contact the flexible wiping member 64, the buckets will retain a fairly well sealed relationship with the said wiping member 64; the rollers permitting suitable and efficient slideable action when the buckets 31 are in contact with the wiping member 64, and the curved extensions 38 providing positive guiding and location for the bucket with respect to the belt, 45 thus preventing any of the contents which have

40

45

50

been accumulated within the bucket from escaping therefrom.

The belting as indicated in Figure 6 is preferably a V belting suitably fitted to the V groove pulleys 30, 33, and 35 respectively, making a continuous conveyer unit. The belting as indicated in Figure 6 is, preferably, recessed or counter-bored at the bottom as indicated at 40 in order to accommodate rivets 41 which are secured to the body of the bucket and by virtue of which the body of the bucket is riveted to the belting 32. Any other suitable fastening or securing means may be utilized.

To connect the silo portion 16 to the housing which supports the shaft 33 which incidentally is geared to a spring motor housed within the motor housing generally designated 43, the side elements 25 and 28 serve to act as an intermediate connection for the hopper between the housing 43 and the silo structure 16. The connecting means is made up of the two side panels 25, provided with a reinforcement member 26 which is to act as a closure for that part of the opening 27 in the silo which is not used, and also to provide an added support for the inclined chute 23 from whence the material conveyed in the buckets is dumped thereupon will slidably accumulate on the platform 24 and by gravitation will be caused to accumulate at the constricted portion between the platform 24 and the pulleys 34 when the buckets 31 in passing will accumulate quantities of the material sufficient to fill the cavities 42 therein, and then continue in the path indicated by the arrow. As heretofore elucidated, the buckets being in contact with the flexible wiping member 64 will retain those contents until the buckets are ready to emerge from the frame-work at opening 77 and thus travel up thru the openings in the silo and over the pulley 30 whence they will reach an inclined position and dump the contents which will come down in a showering effect, if such material as confetti is utilized.

The silo structure being transparent will also permit visibility of the various colors of the confetti and their showering fall within the silo 16 will produce a multicolored effect which should be very pleasing to the eye and which may be further enhanced by the lighting effect provided by the bulbs 21 which may also be multicolored, and as shown in Figure 7 are connected to an electrical source of supply 68. Instead of spring motivated means, electric motive power means is indicated at 71 which may be connected by proper switching means as at 70, the switching means 69 being for the lighting circuit or one switch may be utilized for the operation of the entire circuit of the electric motive power means as well as the lighting. The electric source of supply is connected to the device by means of a female socket 22 imbedded or suitably secured in the base 20 of the invention, and if the invention is to utilize an electric motor it will be wired according to the diagram shown in Figure 7.

The spring motive power means which is housed within the housing 43 is best illustrated in Figures 11, 12 and 14, which comprises a spiral spring 44 which may be secured at 62 to the shaft 72 which is provided with a square exposed shank 45 to be engaged by a suitable key for winding. The spring is anchored at its opposite end to the base 20 of my invention by virtue of rivet means 63. The spring is integrally connected to the ratchet, the ratchet being secured to the shaft 72.

The ratchet 46 is secured to the shaft 72 and 75

is engaged by the pawl 47 mounted on the pivot 48, the flat spring 49 being provided in order to maintain, normally, the pawl in engagement with the ratchet. The ratchet will escape engagement with the pawl 47 when the spring is wound in a clock-wise direction. Once the potential energy in the spring is released and converted into kinetic energy, it will cause the ratchet to turn the gear 50 which is mounted to rotate freely on the shaft 72.

The gear 50 is in mesh with a pinion 57 mounted on a shaft 53 upon which are also mounted suitably the V pulleys 36 and the partitions 51 and 52 act as added bearing support for the shafting which is mounted and is essential for the spring motor drive. Upon the shaft 53 is mounted an intermediate gear 58 which is in mesh with an idler pinion 59 mounted on the shaft 72 ultimately meshing with the pinion 60 secured to the shaft 73 upon which is mounted a fan type of governor generally designated 61 so as to more or less control and govern uniformly the reverse rotation of the spring motorized mechanism when its energy is being expended to operate the conveyer means.

When winding the spring to store potential energy therein, the brake mechanism comprised of the threaded bushing member 54 held in place by a lock-nut and having also an internal thread into which the knurled head screw 55 is secured, the end of the said screw being cupped in order to receive a compressible material so as to provide ideal frictional action when the said screw 55 or the end 56 thereof is brought to bear frictionally against the gear 58, thus holding in check against reverse motion the entire mechanism. When it is desired to allow the device to operate, this brake may be completely released or partially released if it be desirous to further aid the governor in stabilizing the uniform motion and operation of the conveyer system, with its attendant function of causing the buckets to pick up the confetti material and dump the same continually and uniformly causing a pleasing kaleidoscopic, amusing, and educational effect.

Figure 13 more elaborately elucidates the nature of my flexible wiping member 64 which aids in retaining the contents in the buckets 31 when in inverted relationship, and as shown is secured to the frame-work by an angle bracket 66 and rivet means 65. The other end of the wiping member 64 is suitably secured as at 67 to the platform 24.

In operation, my invention is first charged with a suitable amount of confetti. By removing the cap 17 from snapping engagement at the beaded portion 18 and allowing the said confetti to drop down on the inclined chute 23 which is riveted to the silo member 16 at 74, and may be so secured as to permit the said chute 23 to have imparted thereto a slight vibration which would aid materially in causing the contents to accumulate between the constricted portions of the wiping member 64, the pulleys 33, and the inclined auxiliary chute 24. When the motor brake 55 is released, the conveyer belting 32 will move in a continuous motion within its orbit or intended path.

The buckets as heretofore explained, will pick up a suitable amount of material, and are so constructed as to maintain or retain the full capacity of the bucket contents while in inverted position until carried upwardly. Gravity will retain the contents within the bucket until a point is reached below the pulley 30 when the material

will be dumped producing a showering effect. The operation thus will continue to select and pick up material and dump the same and thus produce the very amusing and educational results heretofore more fully elucidated.

At times inspection of the inner portion of the device may become necessary to prevent clogging, and for this purpose I furnish the snap door 44' which fits into the opening 46' by virtue of offset portions 45' so that the device may be 10 readily opened at this point and inspected if it should become clogged by the material used.

The member 75 is a cover to enclose the side cleats 25 and 28. It should also be noted that suitable openings 76, 77, 78 and 79 are provided both in the silo structure and the base housing structure to permit the bucket means 31 to pass the said openings providing sufficient clearance therefor.

Altho I have described rather succinctly a preferred form of my invention, and inasmuch as it is susceptible of many alterations, modifications and improvements, I reserve the right to all such modifications, alterations and improvements lying within the scope and spirit of my invention and within the purview of the foregoing description and the accompanying drawings; my invention to be limited by the subjoined claims.

Having thus described and revealed my invention what I claim as new and desire to secure by 30 Letters Patent is:

1. A device of the character described comprising, transparent silo means, motive power means, hopper means interconnecting the said silo means and the said motive power means, continuous conveyer means operating in an orbit defined by the said silo means motive power means and the said hopper means, bucket means secured to the said conveyer means, and flexible wiping means

having one end secured within the said hopper means the other end thereof being secured to the housing adjacent the said motive power means.

2. A device of the character described comprising, transparent silo means, motive power means, hopper means inter-connecting the said silo means and the said motive power means, continuous conveyer means operating in an orbit defined by the said silo means motive power means and the said hopper means, bucket means secured to the said conveyer means, and wiping means secured in parallel relationship to the said conveyer means adapted to retain sealably material within the said bucket when in inverted position.

3. A device of the character described comprising, transparent silo means, motive power means, hopper means inter-connecting the said silo means and the said motive power means, continuous conveyer means operating in an orbit defined by the said silo means motive power means and the said hopper means, bucket means secured to the said conveyer means, and flexible wiping means secured in parallel relationship to the said conveyer means adapted to retain sealably material within the said bucket when in inverted position.

4. A device of the character described comprising, transparent silo means, motive power means, hopper means inter-connecting the said silo means and the said motive power means, continuous conveyer means operating in an orbit defined by the said silo means motive power means and the said hopper means, bucket means secured to the said conveyer means, and elastic wiping means secured in parallel relationship to the said conveyer means adapted to retain sealably material within the said bucket when in inverted position.

FRANK E. THOMAS.
